CLAIM

The ornamental design for a wire wreath holder, as shown and described.

DESCRIPTION

FIG. 1 is a top, front and right side perspective view of a wire wreath holder in accordance with my invention;

FIG. 2 is a top plan view thereof;

FIG. 3 is a left side view thereof that is a mirror image of the right side thereof;

FIG. 4 is a rear view thereof;

FIG. 5 is a bottom plan view thereof; and,

FIG. 6 is a top, front and right side perspective view of a wire wreath holder in accordance with a second embodiment of my invention; the sole difference residing in the central hook-shaped bar.

The broken line showing of a wreath is for illustrative purposes only and forms no part of the claimed design.
